BENJAMIN A. HOWES, OF NEW YORK, N. Y.

TIE FOR CONCRETE CENTERING.

Specification of Letters Patent.

Patented Apr. 4, 1916.

1,177,950.

Application filed February 6, 1911. Serial No. 606,679.

To all whom it may concern:

Be it known that I, BENJAMIN A. HOWES, of New York city, borough of Manhattan, in the county of New York and State of New York, have invented new and useful Improvements in Ties for Concrete Centering, of which the following is a specification.

This invention relates to means for securing in place the sections of the molds or "centering" which retain the concrete or other plastic mass, forming the wall of a structure, before it has set, which securing means are commonly referred to in practice as "ties."

15 In forming a concrete wall for a building, it is the usual practice to build up the centering on each side of the space to be occupied by the concrete wall by laying up boards or planks edge to edge so that retaining walls 20 for the concrete, before it has set, are formed on both sides. To secure the sections, usually planks or boards, of the centering, ties may be employed, which ties extend into the concrete space between the retaining walls 25 and engage with the retaining walls. When the concrete is filled in between the retaining walls, the ties become embedded. After the concrete has set to the desired degree, the retaining walls are removed when the ties project 30 from the concrete wall. These projecting ends of the ties must be removed in order that the surface of the wall may be smooth and present a slightly appearance. It is a further desideratum that the wall shall not 35 be marred in removing the projecting ends of the ties, and further that the wall shall remain water-tight so that moisture cannot pass through the wall from one side to the other.

40 It is an object of the present invention to provide an efficient tie for securing centering which shall permit the easy removal of the ends projecting from the concrete after the centering has been taken down, and without 45 marring the wall.

It is a further object of the invention to provide a tie of which the projecting end may be removed without impairing the water-tight character of the wall.

50 Other objects of the invention will appear hereinafter.

In the accompanying drawings, which illustrate the invention, Figure 1 is a side view of a tie embodying the invention; Fig. 55 2 is a cross section on the line A—B of Fig.

1; Fig. 3 is a view, similar to Fig. 1, of a tie like that shown in Figs. 1 and 2, having its bent ends sharpened and adapted for use as driven fastenings; Fig. 4 is a cross section of a tie the same as shown in Fig. 1 or Fig. 3 but having a polygonal cross section. Fig. 5 is a transverse section of a concrete wall with sections of centering applied thereto, showing the relations of the wall, centering and ties, when the centering is in retaining position. Fig. 6 is a view similar to Fig. 5 showing the manner of removal of centering sections, the sections upon one side having been taken down and the projecting ends of ties upon that side having been removed, and Fig. 7 is a side elevation of a tie having a cross-section as shown in Fig. 4.

Referring to the drawings, and first to Figs. 1 and 2, the tie comprises a rod 1 of circular cross section, having its ends 2 and 3 bent at an angle with the main axis of the tie, and a bend 4 forming a lateral extension at an intermediate portion. Adjacent to the ends, and between the bend 4 and the ends, are notches 5 and 6 which serve to reduce 80 and weaken the sections of the tie at the points referred to.

In Fig. 5 is shown centering for a concrete wall. On one side it is built up of the sections 7, 8 and 9 (usually wooden boards) 85 laid edge to edge, while on the other side the retaining wall is similarly laid up of the sections 10, 11 and 12.

The ties extend from between adjacent sections in one retaining wall, through the space for the concrete, and between adjacent sections of the opposite retaining wall. In each retaining wall a tie engages with a section, to prevent its outward movement, upon one side only of the tie. The arrangement of centering sections and ties is clearly shown in the drawing. It will, of course, be understood that the arrangement may be extended to any desired extent by adding sections and ties.

The concrete 13 is filled in between the retaining walls and embeds the ties as shown. As the concrete sets, it firmly grips the ties so that water-tight joints are formed and moisture cannot pass along the tie from one side of the concrete wall to the other.

The centering may be taken down section by section by pulling out the bottom of a section which it is desired to remove, as shown by the section 8 of Fig. 6, and then 11

moving it downwardly to disengage it from the tie at its upper edge. It will be observed that the bottoms of the sections are not engaged by the ties to prevent those bottoms from being pulled outwardly as described, each tie engaging, to prevent such movement, with the section on one side only.

After the centering has been taken down as described, the ends of the ties will project 10 from the concrete wall and must be removed to make the wall smooth and sightly. This can be done by gripping each projecting end with a suitable tool and twisting it, when the tie will part at the adjacent weakened section, just inside the face of the wall. The severed end can then be removed and the hole pointed with cement if desired.

The tie shown in Figs. 1 and 2, being formed of a rod of circular cross section, the 20 portions between the weakened sections and the ends are of circular cross section. This permits these portions to be easily turned about their axes in the concrete, in twisting them off, while the lateral extension 4 prevents turning of the intermediate portion of the tie. By removal of the tie-end in the 25 manner described, the intermediate portion of the tie, which remains in the wall, does not have its water-tight relation with the concrete impaired so that the concrete wall remains water-tight.

It will, of course, be understood that a tie having its intermediate portion of any suitable conformation which would engage 35 with the concrete to resist turning, could be used.

The cross section of the portion between a weakened section and its adjacent end, need 40 not be circular in all cases but may be bounded by a polygon having its sides at equal distances from its center, as shown in Fig. 4. The number of sides of the polygon may vary, and, of course, the circle is the limit of the polygon as its sides 45 are increased in number.

With the bent ends of the tie blunt, as in Fig. 1, holes or recesses would ordinarily have to be prepared in the edges of the centering sections to receive these ends. The 50 sharpened ends shown in Fig. 3 can be driven into the edges of the sections and the latter require no special preparation in this regard.

It will be apparent that various modifications and changes can be made of the structures shown in the drawings without departing from the spirit of my invention, which is not therefore limited to the structures shown.

60 What I claim is:

1. A tie for concrete centering of substantially circular cross section having a lateral extension between its ends and a weakened section between said extension and each end and remote from the face of the

wall to be formed, the tie ends being adapted to be twisted off at the weakened sections, the said cross-section permitting the twisting without marring the face of the wall.

2. A tie for concrete centering having a lateral extension and a weakened section between said extension and each end and remote from the face of the wall to be formed, the tie being substantially circular 75 in cross section between each of said weakened sections and the end to which it is adjacent, the tie ends being adapted to be twisted off at the weakened sections, the said cross-section permitting the twisting without marring the face of the wall.

3. A tie for concrete centering having a portion adapted to resist turning of the tie in a mass in which it may be embedded, a weakened section between said portion and 85 one end and remote from the face of the wall to be formed, said tie between said weakened section and said end being of substantially circular cross section, the tie end being adapted to be twisted off at the 90 weakened section, the said cross-section permitting the twisting without marring the face of the wall.

4. A tie for concrete centering having a weakened section adjacent to one end but 95 inside the face of the wall to be formed, said tie between said weakened section and said end being of substantially circular cross section, the tie end being adapted to be twisted off at the weakened section, the said 100 cross-section permitting the twisting without marring the face of the wall.

5. A tie for concrete centering having an intermediate portion adapted to resist turning of the tie in a mass in which it may be embedded, a weakened section between said portion and each end and remote from the face of the wall to be formed, said tie between each weakened section and its respective end being of substantially circular cross section, the tie ends being adapted to be twisted off at the weakened sections, the 105 said cross-section permitting the twisting without marring the face of the wall.

6. A tie for concrete centering having 115 weakened section adjacent to each end but inside the faces of the wall to be formed, said tie between each of said weakened sections and its respective end being of a substantially circular cross section, the tie ends being adapted to be twisted off at the weakened sections, the said cross-section permitting the twisting without marring the face of the wall.

7. A tie for concrete centering comprising 125 a rod, substantially circular in section, bent at an intermediate point to form a lateral extension and having a weakened section upon each side of said extension and remote from the face of the wall to be formed,

and having its ends bent at an angle to form a fastening to the centering, the tie ends being adapted to be twisted off at the weakened sections, the said cross-section permitting the twisting without marring the face of the wall.

8. The combination in a mold for concrete or other plastic material, of a plurality of mold sections on each side of the space for the material to be molded, a tie extending between adjacent sections at each side of said space but engaging one only of the sections between which it extends to prevent lateral movement thereof, said tie having an intermediate lateral extension or offset and a weakening notch between its end and said offset and remote from the face of the wall to be formed, said notch and offset being located within said space and said tie, between said notch and its end, being of a substantially circular cross-section, the tie end being adapted to be twisted off at the notch, the said cross-section permitting the

twisting without marring the face of the wall.

9. A tie for concrete centering consisting of an integral bar of substantially circular cross-section, said bar being bent at an intermediate portion to form a lateral extension or offset, having its ends bent at right angles to form section engaging means and notches in said bar between said lateral extension and its ends, said notches being remote from the faces of the wall to be formed, and the tie ends being adapted to be twisted off at the notches, the said cross-section permitting the twisting without marring the walls.

In testimony whereof I have hereunto set my hand this twenty-eighth day of January 1911, in the presence of two witnesses.

BENJAMIN A. HOWES.
